Primary Examiner — Catherine A Tuttle(74) *Attorney, Agent, or Firm* — Cook Alex Ltd.; R. Blake Johnston**CLAIM**

The ornamental design for a rocking toy, as shown and described.

DESCRIPTION

FIG. 1 is a front, side and top perspective view of the rocking toy showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, side and top perspective view thereof.

The broken lines in FIG. 7 depict portions of the bottom surface that form no part of the claimed design.

1 Claim, 5 Drawing Sheets(56)
